(57) **CLAIM**

The ornamental design for bench, as shown and described.

DESCRIPTION

1. Bench
- 1.1 : Perspective
- 1.2 : Front
- 1.3 : Left
- 1.4 : Top
- 1.5 : Right
- 1.6 : Bottom
- 1.7 : Back

The parts shown by means of broken ones in the reproductions are not part of the claimed design.

The bench is shown with a symbolic break in its width. The appearance of any portion of the article between the break lines forms no part of the design.
